UNITED STATES PATENT OFFICE.

RHODES ARNOLD, OF WALTHAM, MASSACHUSETTS.

NOSE-PIECE FOR BRIDLES.

SPECIFICATION forming part of Letters Patent No. 226,954, dated April 27, 1880.

Application filed March 3, 1880. (Model.)

To all whom it may concern:

Be it known that I, RHODES ARNOLD, of Waltham, in the county of Middlesex and State of Massachusetts, have invented a new and useful Improvement in Nose-Pieces for Bridles, of which the following is a specification.

My invention relates to a means for lessening the difficulty of holding in a horse addicted to "pulling hard on the bit," as it is technically termed.

The invention consists in the combination, with the bit and the head-piece of a bridle, of straps for counteracting the pressure of the bit on the mouth and lower jaw of the animal, as hereinafter described.

In the accompanying drawings, Figure 1 is a perspective view of my improvement applied to the bit, and Fig. 2 is a detail view of the nose-piece.

Similar letters of reference indicate corresponding parts.

A represents the head-piece, B the bit, and C the cheek-piece, of an ordinary bridle. D is a strap which passes from the bit-rings b b across the front of the nose of the animal. The portion between the bit-rings is stiffened by a wrapper, E, which carries two strap-keepers, d d, and also has attached to it a strap, G, which passes upward in front of the

nose of the animal and engages with a buckle, a, on the head-piece A. In the strap D, on either side of the wrapper E, is a slot, s.

The parts are connected together as follows: The bit-rings b b are turned sidewise and passed through the slots s. The ends of the strap D are then passed through the bit-rings and brought together and buckled, as shown in Fig. 1. The cheek-pieces C C are then buckled to the bit-rings, and the strap G is buckled to the head-piece.

The bridle being in place on the head of the animal, the straps D and G are adjusted so as to prevent the bit from pressing too hard either on the lower jaw or grinders or in the crotch of the mouth. As the strap D is stiffened by the wrapper E, said strap does not press upon the nostrils, and consequently does not interfere with the horse's breathing.

Having thus described my invention, I claim as new and desire to secure by Letters Patent—

The strap D, stiffened by the wrapper E, and having the slots s s, in combination with the bit and rings of a bridle, substantially as and for the purpose herein described.

RHODES ARNOLD.
